UNITED STATES PATENT OFFICE.

CHARLES F. SMITH, OF MILWAUKEE, WISCONSIN, ASSIGNOR TO SMITH ENGINEERING WORKS, OF MILWAUKEE, WISCONSIN, A CORPORATION OF WISCONSIN.

GRAVEL WASHER.

Application filed September 24, 1926. Serial No. 137,494.

This invention relates to improvements in gravel washers.

Gravel washers now in general use are open to the objection that they do not wash out sticky clay from the gravel.

It is, therefore, the primary object of the present invention to provide a cylindrical screen gravel washer so constructed as to efficiently wash out sticky clay and like foreign substances.

A further object of the invention is to provide a gravel washer having a scrubber in which the material is thoroughly churned up by lifting blades.

15 A further object of the invention is to provide a gravel washer in which the larger boulders are retarded within a certain section and as the device revolves, the boulders perform a "ball mill" action to grind up any 20 clay, shale, slate, or other soft rock in the aggregate.

A further object of the invention is to provide a gravel washer in which the sand and pebbles can not in any way retard and 25 blanket the grinding agencies, or embed themselves in the clay to armor this material, and in any way retard or hinder the "ball mill" action.

30 A further object of the invention is to provide a gravel washer designed to effectively retain the large aggregate.

A further object of the invention is to provide a gravel washer in which sprays are introduced for the full length of the scrubbing 35 section and the dirty water is flushed out as fast as it is used, and in which, as the material progresses toward the end of the scrubber, it is continuously flushed with clean water while the dirty water is flushed away.

40 A further object of the invention is to provide a gravel washer which is of very simple construction, is strong and durable, and is well adapted for the purposes described.

45 With the above and other objects in view, the invention consists of the improved gravel washer, and its parts and combinations as set forth in the claims and all equivalents thereof.

50 In the accompanying drawings in which the same reference characters indicate the same parts in all of the views:

Fig. 1 is a horizontal sectional view of the improved gravel washer;

55 Fig. 2, is a side view thereof;

Fig. 3, is an end view thereof;

Fig. 4, is an opposite end view;

Fig. 5, is a fragmentary detail view partly in section, and on a larger scale; and

Fig. 6, is another enlarged fragmentary 60 detail view, partly in section.

Referring now more particularly to the drawings, it will appear that the numeral 10, indicates a supporting structure having a bearing 11 at one end and a pair of bearing 65 12 at the other end. The improved gravel washer, generally indicated by the numeral 13, is mounted longitudinally on said supporting structure and a shaft 14 mounted in a bearing 15 is journaled in the 70 bearing 11 formed in the rear end of the gravel washer. The opposite end portion of the gravel washer carries an external, annular flange 16 adapted to ride on the bearing wheels 12. Hence, by means of the bearings 75 and wheels, the gravel washer is revolvably mounted with respect to the supporting structure.

The gravel washer includes an inner elongated cylindrical member 17 termed a 80 washing screen and an outer cylindrical member 18 termed a jacket, the jacket being of less length than the washing screen and mounted with respect thereto as shown in Fig. 2. The said members 17 and 18 are 85 connected by means of angular plates 19.

The inner or rear end of the washing screen is closed by means of a disc casting having attached thereto a bevel ring gear 20 adapted to mesh with a pinion gear 21 90 carried on a shaft 22 at right angles to the longitudinal plane of the screen, the shaft 22 being journaled in a bearing 23 carried by the end portion of the supporting structure 10. The outer end portion of the 95 shaft 22 carries a pulley wheel 24 for connection with a source of power by means of a belt (not shown). Obviously, by means of the gears described, the gravel washer may be revolved. The forward or outer 100 end of the washing screen is partially closed by a retainer ring 25 formed with a circular opening 26 of substantial size to permit the introduction of material into the screen. The interior of the screen is also divided by 105 two or more retainer rings 27 and 28, forming a plurality of compartments 29, 30 and 31, the compartment 31 being of greater size than the other compartments.

The forward compartments 29 and 30 pro- 110

vide what is known as the scrubbing section and secured to the interior walls of the screen forming the scrubbing section are longitudinally extending lifting blades 32. The 5 outermost portion of the screen forming the scrubbing section is unperforated, as at 33. The remaining portion of the screen enclosing the compartments 29 and 30 is formed with a plurality of small apertures 34. The 10 portion of the screen enclosing the large compartment 31, except for the extreme end portion thereof, is formed with a plurality of apertures 35 substantially larger than the apertures 34.

15 The outer jacket 18 is formed in two sections 37 and 38 secured together by means of plates 36, as shown in Fig. 5. The portion 37 of the jacket which covers the scrubbing sections of the washing screen is provided 20 with perforations 39 of a small size and this section of the member 18 provides a sand jacket. The section 38 of the member 18 is formed with larger perforations 40 to provide a fine gravel jacket.

25 The method of washing gravel by means of the improved washer is as follows:

The improved gravel washer is adapted for use in gravel plants and receives the material usually after it has passed through a 30 washing box. The gravel washer is revolved by means of the mechanism heretofore described and the material is introduced into the open end of the washing screen into the compartment 29. It should also be understood that the material is subjected to sprays 35 of water during its entire stay in the scrubbing section of the gravel washer. In the scrubbing section or compartments 29 and 30, the material is thoroughly churned up by 40 the lifting blades 32, and as it progresses toward the retainer rings 27 and 28, sand and dirty water are flushed through the perforations of the scrubbing section and the sand jacket. The fine aggregate passes the 45 sand jacket and is conveyed to other mechanism for further operations. The boulders and small pebbles are retained in the

scrubber and cascade around. The small pebbles pass by the retaining rings 27 and 28 into the compartment 31, but the bigger boulders are held back and a ball mill action results which grinds up the clay, shale, slate and other soft rock in the aggregate within the scrubbing section.

It will thus be seen that in the improved 55 gravel washer an effective "ball mill" action is provided for within the scrubbing section and the material is continually flushed with clean water through the entire length of the scrubbing section, provision being made for 60 the draining off of dirty water. Also the gravel washer is of simple and novel construction, and is well adapted for the purposes set forth.

What I claim as my invention is:

1. A revoluble gravel washer, comprising a cylindrical perforated washing screen, a cylindrical perforated jacket surrounding the screen, the perforations of both members being of graduated sizes and extending substantially the length of both members whereby water and material may be flushed therethrough at any point, transverse retainer rings within the screen, and lifting blades 70 within a portion of the screen and extending longitudinally parallel with the axis of the screen.

2. In a revoluble gravel washer, a cylindrical perforated washing screen having perforations of graduated sizes and extending substantially the length of said member whereby water and material may be flushed therethrough at any point, transverse retainer rings within the screen and dividing it into a scrubbing section and a gravel section, the rings serving to restrict the removal of large material from the scrubbing section to the gravel section, longitudinally extending lifting blades within only the scrubbing section and extending parallel 90 with the axis of the screen, and means for revolving the gravel washer.

In testimony whereof, I affix my signature.

CHARLES F. SMITH.
